UNITED STATES PATENT OFFICE.

KINZIE KERN GITTINGS, OF CHILHOWEE, MISSOURI.

HAY-PRESS.

SPECIFICATION forming part of Letters Patent No. 694,626, dated March 4, 1902.

Application filed April 18, 1901. Serial No. 56,395. (No model.)

To all whom it may concern:

Be it known that I, KINZIE KERN GITTINGS, a citizen of the United States, residing at Chilhowee, in the county of Johnson and State of Missouri, have invented certain new and useful Improvements in Hay-Presses; and I do hereby declare the following to be a full, clear, and exact description of the invention, such as will enable others skilled in the art to which it appertains to make and use the same.

My invention relates to self-feeding attachments for hay-baling machines; and my object is to provide reliably-efficient mechanism designed as an attachment which may be readily applied to use upon almost any variety of hay-baling machine as now commonly constructed.

The prime object of my invention is to not only provide feeding mechanism which will introduce the hay or other material to be pressed into bales into the receiving-chamber prior to its entrance into the compression-chamber, but I have also provided automatic means for delivering to the compression-chamber what is commonly designated a "division-block," designed to determine the length or size of the bale compressed.

The preferred construction deemed necessary to provide the several coöperating elements constituting my complete automatic or self-feeding attachment for hay-balers will be clearly described in the following specification and illustrated in the accompanying drawings, in which—

Figure 1 is a perspective view of my invention as applied to use. Fig. 2 is a longitudinal vertical section of the device employed to force the hay into the receiving-chamber. Fig. 3 is a longitudinal vertical section showing my improved feeding attachment and also showing a portion of the hay-baling machine proper. Fig. 4 is a perspective view showing certain operative parts illustrated in Fig. 3. Fig. 5 is a perspective detail view of the holder designed to receive and deliver the division-block as required. Fig. 6 is a perspective view of one of the division-blocks.

In order to conveniently refer to the several elements of my invention and the coöperating accessories, numerals will be employed,

the same numeral referring to a similar part throughout the several views.

While my invention proper does not relate to the general construction of a baling-machine, yet for convenience of description I will show in the drawings such portion of an ordinary baling-press as will fully illustrate a practical application of my ideas to actual use.

Referring to the numerals on the drawings, 1 and 2 designate the supporting-beams or base-sections upon which is erected a suitable elongated casing, as is usual, designed to accommodate the receiving-chamber and also the compression or baling chamber, the receiving-chamber being indicated by the numeral 3, while the compression-chamber is designated by the numeral 4, the walls of said chambers being properly reinforced and sustained, as is common, by a suitable framework, as indicated by the numeral 5, all constructed as is usual in the manufacture of hay and cotton baling machines.

The hay is introduced into the opening (indicated by the numeral 6) formed on the top of the receiving-chamber 3 and is from thence forced into the compression-chamber 4 by the reciprocating plunger-head or compression-block 7, operatively connected with the driving shaft or pitman 8, the latter being supported on its outer free end by the crank-shaft 9, properly journaled in bearings 10, located on the outer ends of the base-sections 1 and 2. The compression-head is reciprocated by any suitable power, the object, as is obvious, being to compress the hay or other substance into a compact form for storage or shipment.

I will now proceed to describe the special features comprising my automatic self-feeding attachment, and in order to reliably anchor the framework carrying the operating parts of my feeding apparatus I locate at a convenient point upon the base members 2 suitable standards 11, to the upper ends of which I secure in any preferred way the outer ends of the members 12, the opposite ends of which rest directly upon the contiguous part of the compression-chamber. The members 12 carry the standards 13, secured in position in any preferred way and properly reinforced

and sustained by a cross-section 14 and suitable braces 15 in order that said standards may be held rigidly in an upright position, and thereby afford a seat upon their upper ends for suitable bearings designed to receive the shaft 16.

The shaft 16 is properly connected to the walking-beam 17, the outer free end of the walking-beam being pivotally connected by 10 means of the link-section 18 to the inner end of the pitman 8, the opposite end of the beam being pivotally connected to the upper end of the feeder 19, carrying upon its lower end the hay-engaging blocks 20, properly secured to 15 the feeder 19 by bolts or otherwise, as more clearly illustrated in Fig. 2. This plunger 19 is of two like parts one on each side of the end of the walking-beam as seen in Fig. 1, and in the center slot the lever 22 is pivotally 20 connected therewith.

The outer sides of the feeding-blocks 20 are preferably reinforced, as by the metallic plate 21, having its extended lower edge properly serrated, whereby the hay or other substance 25 to be delivered into the feeding-chamber will be more readily engaged.

In order to control the movement of the feeder 19 and accompanying feeding-blocks 20, I provide the controlling-lever 22, one end 30 of which is pivotally connected to the door-sections 23, properly hinged to the contiguous end of the members 12, while the opposite end of said lever is pivotally connected to the feeder 19, the extreme free end of the lever 35 being provided with the hook member 24, adapted to engage and force downward the division-blocks 26, which latter are designed for dividing the compressed material into bales of proper length ready to be wired or 40 otherwise secured. The hook part engages over the upper edge of the division-blocks, as seen in Fig. 1. The division-blocks 26 are properly held in position ready to be forced downward by the hook member 24 by means 45 of what is commonly designated the "guiding member" or "block-dropper" 25, which latter may be placed under the ready control of the operator by pivotally connecting the same to the controlling-rod 28, the outer end 50 of said rod being pivotally secured to the operating-lever 29, said lever being pivotally secured to a contiguous part of the frame, as indicated by the numeral 30.

In Fig. 4 it will be observed that guideways 55 or tracks 31 are provided upon the upper part of the compression-chamber, and said tracks are designed to receive the weight of the block-dropper or guiding member 24, and in order to hold said dropper reliably in position 60 upon said tracks the depending guideways or brackets 32 are attached to the block-holders 25 at such point thereon as will insure that said brackets will each rest upon its respective track.

65 It will be understood that the block-dropper rests horizontally upon the tracks until lifted into position in order to drop the block.

In order to prevent the block proper, 25, from casually slipping off the ends of the track 31, and thus falling into the feeding-chamber, I 70 provide the ears 33, each of which is provided with a suitable aperture of proper size to loosely receive one of the track-sections, and since said track-sections are so shaped at their inner ends that they will extend slightly over the opening 6, through which the hay is introduced, it is clear that the guiding or division block holder 25 may be forced into such position as will prevent the hay or the like from engaging the contiguous edge of the 80 opening 6 when the division-block is to be forced downward into the receiving-chamber by the hook 24, as clearly illustrated in Fig. 3 and other views.

It will be observed that the compression-head 7 and the feeder 19 have a relative reciprocating movement—that is to say, when the compression-head 7 is withdrawn the feeding feeder 19 and accompanying blocks 20 are forced downward, and when the plunger is 90 elevated the head is forced inward, and it is therefore obvious that the process of feeding the hay or the like into the machine will be very greatly facilitated.

Since the walking-beam is pivotally connected by means of the link 18 to the pitman 8 or the head 7, as the case may be, said relative movement of said parts must unerringly continue as long as the machine is operated. The division-block 25 may be made in any 100 preferred way most suitable for the purpose of holding the block 26 in place, so that it can be held over the feeding-chamber near the inner end of the compression-chamber ready to be forced downward by the hook 24 105 when required. The holder may be made of suitable heavy sheet metal so bent at the ends as to provide the guiding-flanges 34, said flanges being a proper distance apart to enable the division-block to be loosely received 110 between them.

In order to prevent the block 26 from casually dropping downward into the compression-chamber, I provide, preferably upon the outer side, the depending spring 35, which is 115 riveted or otherwise secured to the holder, the lower free end of the spring being bent inward, so as to lie in the path of the downward movement of the block, and it is therefore obvious that when said block is engaged 120 by the hook 24 the tension of the spring will be overcome and the block permitted to move downward into position.

In Figs. 3 and 4 I have illustrated by means of the lever 29 how the division-block holder 25 may be easily manipulated and controlled by the operator standing upon the ground. This construction will be desirable where the same person attends to the wiring of the bales as they are ready to leave the machine. 130 When, however, it is desired to operate the holder and thus deliver the division-blocks 26 by the person standing on the feeding-platform, then I prefer to dispense with the

lever 29 and the controlling-rod 28 and substitute therefor the controlling-lever 36, secured in position on a contiguous part of the frame, preferably upon one of the members 5 12, as indicated by the numeral 37. The lower end of the lever 36 is pivotally connected to the controlling-shaft 38, which extends into pivotal connection with one edge of the block-holding member 25, as indicated by the 10 curved terminal 39.

If preferred, a suitable rack-bar 49 may be provided, adapted to be engaged by a manually-controlled detent, as indicated by the 15 numeral 41, whereby the lever may be adjusted and set in any desired position. As 20 is common, I prefer to so form the division-blocks 26 that they will have the transversely-disposed grooves 42, adapted to permit the baling-wires to be readily introduced in position ready to be secured.

Having thus fully described the construction and combination of parts required to produce my self-feeding attachment for baling-machines, the operation or manner of using 25 the same may be stated to be as follows: When the machine is operated to drive the compression-head 7 within the compression-chamber, the desired quantity of hay is placed under the feeding-blocks 20, so as to be in 30 proper position when the head 7 is withdrawn to be forced downward by said feeding-blocks 20 into the receiving-chamber 3. It is therefore obvious that when the head 7 again moves inward the hay in advance of it will be forced 35 by said head from the feeding-chamber into the compression-chamber 4, and thus form an addition to the bale that is being made. During the process of feeding the hay into the receiving-chamber 3 the operator will 40 properly manipulate the lever 29 or 36, as the case may be, so as to bring the division-block holder 25 into the vertical position over the edge of the opening 6 in the feeding-chamber, the holder being properly inclined, so as to 45 bring the upper edge of the division-block in the path of the downwardly-moving hook 24, thereby causing said hook to contact the division-block and force it into the feeding-chamber when it may be deemed necessary 50 to start another bale. By the operation of the parts just described it will be seen that the feeding process or the work of introducing hay into the feeding-chamber is in no wise interrupted or interfered with, as would be 55 the case if it should be necessary to manually introduce the division-block in place. When the division-blocks are introduced by hand, as is common, the machine must be stopped until the block is properly adjusted, 60 as otherwise the operator would incur great danger by placing his hands within the feeding-chamber during the act of adjusting the division-block.

By the use of my improved automatic feeding and block-introducing mechanism the division-blocks are promptly delivered at required intervals without interrupting the in-

termittent action of the feeding mechanism proper, and it is therefore clearly apparent that by the use of my invention the capacity 70 of the baling-machine is greatly multiplied, as there is no necessity of losing a single operation or feed. The block-introducing mechanism being much more powerful than hand-power, it is possible to feed or introduce a larger 75 bunch of hay than would be possible without the use of my invention.

By providing the feeding-blocks 20 to force the hay downward into the receiving-chamber much larger quantities of hay can be introduced 80 than would be possible if forced in said chamber in the usual manner, as with a fork or by the pressure of the feet of the operator.

By the use of my invention many serious 85 accidents will be avoided, as it is well known to be a dangerous operation to introduce the feet into the receiving-chamber for the purpose of initially compressing the hay therein. The upper edge of the block-holder should 90 be inclined outward and a division-block dropped in place between the flanges 34, and after a sufficient quantity of hay has been compressed to form a bale of the desired size 95 the block-holder is moved, so that at the next downward movement of the hook 24 the block will be forced in place, as above set forth.

While I have described the preferred construction which may be adopted in manufacturing my improved self-feeding attachment 100 for hay-baling machines, it will be understood that I desire to comprehend in this application all substantial equivalents and modifications which may be considered to fall fairly within the scope and purview of my invention, 105 and I therefore do not wish to be confined strictly to the exact showing herein presented.

Having thus fully described my invention, what I claim as new, and desire to secure by 110 Letters Patent, is—

1. The combination with the reciprocatory feeder, a division-block holder adapted to receive division-blocks and a rocking beam operatively connected with said feeder, of a 115 controlling-lever pivotally mounted on the feeder and means carried by said lever to engage a division-block in said holder, substantially as and for the purpose specified.

2. The combination with a reciprocatory 120 feeder, a division-block holder adapted to receive division-blocks and a rocking beam operatively connected with said feeder, of a controlling-lever pivotally mounted on the feeder, means carried by said lever to engage 125 a division-block in said holder, and hinged door-sections connected to one end of said lever, as set forth.

3. The combination with a reciprocatory 130 feeder, a division-block holder adapted to receive division-blocks, and a rocking beam operatively connected with said feeder, of a controlling-lever mounted pivotally on the feeder, means carried by said lever to engage

a division-block in the holder, hinged door-sections connected to one end of said lever, and tracks upon which said holder rests horizontally till lifted into position to drop the blocks, as set forth.

4. The combination with a reciprocatory feeder, a division-block holder adapted to receive division-blocks, and a rocking beam operatively connected with said feeder, of a controlling-lever pivotally mounted on the feeder, means carried by said lever to engage a division-block in the holder, hinged door-sections

connected to one end of the lever, tracks upon which the holder rests horizontally till lifted into position to drop the blocks and means for preventing the block proper from accidentally dropping off the ends of the tracks, as set forth.

In testimony whereof I affix my signature in presence of two witnesses.

KINZIE KERN GITTINGS.
